DOOR OPERATING DEVICE

Knut G. Etsel and John Christensen, Chicago, Ill.

Continuation of application Serial No. 737,000,
July 26, 1934. This application October 2, 1939,
Serial No. 297,610

3 Claims. (Cl. 268—3)

This invention relates to apparatus for opening doors and has for its object to provide a new and improved device of this description. The invention has as a further object to provide means for opening any kind of doors which may be actuated from a distant point. The invention has as a further object to provide a door opening device by means of which the door may be opened from a distant point or opened by means of the normal door opening mechanism, the opening apparatus controlled from a distant point not interfering with the normal manual opening means. The invention has as a further object to provide a door opening device which may be used for any door and which is particularly adapted for the doors of automobiles and permits the door to be opened by the driver without the necessity of touching the door or the handle thereof.

The invention has as a further object to provide a door opening apparatus which may be actuated from any suitable point at a distance from the door and which will unlock the door when so actuated and cause the door to swing open. The invention has as a further object to provide such a door opening device which is brought into operative condition whenever the door is closed. The invention has as a further object to provide a door opening mechanism which in no manner interferes with the normal manual operation of the door from either a closed or open position. The invention has as a further object to provide a door opening mechanism which is selective and which does not depend on sequence, as it can be made to cause the door to open if closed, or to close if opened, whether the previous cycle has been operated through manual or mechanical means. The invention has further objects which are more particularly pointed out in the accompanying description.

Referring now to the drawings, wherein for purposes of illustration we have shown one form of mechanism applied to an automobile door, Fig. 1 is a side view of an automobile having one form of the apparatus applied thereto;

Fig. 2 is a perspective view showing the instrument board and associated parts of the automobile;

Fig. 3 is a view showing the mechanism at the door;

Fig. 4 is a sectional view taken on line 4—4 of Fig. 3;

Fig. 5 is a sectional view taken on line 5—5 of Fig. 3;

Fig. 6 is a view showing the electric circuits for one form of the device;

Fig. 7 is a view showing the door in its closed position, with parts broken away;

Fig. 8 is a view showing a modified construction;

Fig. 9 is a sectional view taken on line 9—9 of Fig. 8;

Fig. 10 is a sectional view taken on line 10—10 of Fig. 8;

Fig. 11 is a view showing the door in its closed position, with parts broken away;

Fig. 12 is a view of an automobile body, with parts broken away, showing the interior thereof with one form of mechanism in position;

Fig. 13 is a front elevation of a portion of the operating mechanism including the motor;

Fig. 14 is a view showing an ordinary lock adapted for the operating cable of the device;

Fig. 15 is a sectional view taken on line 15—15 of Fig. 17;

Fig. 16 is a sectional view taken on line 16—16 of Fig. 17;

Fig. 17 is a top view of the mechanism showing the motor and associated parts;

Fig. 18 is a sectional view taken on line 18—18 of Fig. 17;

Fig. 19 is a sectional view taken on line 19—19 of Fig. 17;

Fig. 20 shows a similar control circuit which may be used in connection with the apparatus.

Like numerals refer to like parts throughout the several figures.

This is a continuing application of the applicants' copending original application Serial No. 737,000, filed July 26, 1934.

For purposes of illustration, we have shown the device in connection with an automobile door, but it is of course evident that it may be used with any other door. Generally speaking, the device consists of mechanism which may be operated by a motor and which may be controlled from a point distant from the door, as by any switch device which may be operated by hand or through the agency of push buttons, levers, or by foot pedals, or by any other suitable means. When the device is operated from this distant point, the bolt of the door is moved to unlock it and the door is thrown open by means of a suitable spring properly arranged for this purpose.

Referring now to the particular mechanism illustrated, which shows one form of the device, there is provided a motor 1, see Figs. 13, 16, 17, 18 and 19, preferably with a worm drive and train of gears 2, and driving main shaft 3, having a

ratchet 4 keyed to it and arranged to drive the drum 6, see Fig. 19, through a pawl 5 mounted on said drum in a counter-clockwise direction, but unable to rotate said drum in a clockwise direction. A connecting rod 7 has its lower end pivoted on a stud mounted on the face of the drum 6, and has its upper end, which is slotted, pivoted on a stud mounted on the face of the bell crank 8 and placed in such a position that a complete revolution of the drum 5 will cause the bell crank 8 to transcribe an arc, whose limits conform with the sides of an angle having its apex at the center of the rocker shaft 9.

The rocker shaft 9 is made of two sections, details of which are shown in Fig. 18, which is a sectional view through line 18-18 of Fig. 17, the anterior section having an enlarged portion bored out to accommodate an extension of the posterior section which is carried through the bearing 10 to provide support, thereby eliminating any binding between the two sections, other than friction.

The rocker shaft 9 has mounted upon it the following members, reading from front to rear, a governor damper worm gear 11, a spring drum 12, the bell crank 8, a gear housing 14, a spur gear 15, a second spur gear 16, a cable sheave 17, and a cam operated arm 18. The members 11, 12, 8 and 15 are torsionally connected to the anterior section of the rocker shaft 9. The members 16 and 18 are torsionally connected to the posterior section of the rocker shaft 9. The members 14 and 17 are free to rotate.

The gear housing 14 carries a shaft 19 parallel to rocker shaft 9 and extending through bearings in the side walls of the gear housing 14. A cable drum 20 and a wide pinion gear 21 are keyed to this shaft 19. The pinion gear 21 meshes with the spur gear 16 and with the intermediate gear 22, which in turn is meshed with the spur gear 15. The intermediate gear 22 rotates on the stud 23, which extends inwardly from one of the side walls of the gear housing 14.

When the motor 1 is caused to operate in such a direction as to rotate the drum 5 in a counter-clockwise direction, it will transmit during one-half revolution, a rotary movement to the anterior section of the rocker shaft 9, through the connecting rod 7 and bell crank 8, such rotary motion being only a part of a revolution. This counter-clockwise partial rotation is imparted to the spur gear 15, as well as to the other members keyed to this part of the rocker shaft 9, and causes the intermediate gear 22 to drive the pinion gear 21 and cable drum 20 in a counter-clockwise direction. One end of the pinion gear 21 being in mesh with the spur gear 16, a counter-clockwise rotation of said pinion gear will cause it to move itself around the gear 16 in a counter-clockwise direction, rotating the gear housing 14 with it. The extent of this rotation is determined by the radius of the circle scribed by the stud on the drum 5, the radius of the arc scribed by the stud on the bell crank 8 and the ratio of the spur gear 15 to spur gear 16.

A cable 24 is weaved through a groove in the sheave 17 upward on its right side and following its circumference around the top and leading off to the left to the cable drum 20 to which it is anchored in such a way as to cause said cable to wind up on the upper periphery of said drum when it is being rotated in a counter-clockwise direction. This is shown in detail in Fig. 16, which is a sectional view through line 16-16 of Fig. 17. The rotary movement of the gear hous-

ing 14 as a whole around the rocker shaft 9 causes the cable 24 to be pulled around the sheave 17, in addition to the amount wound up on the drum 20 as it rotates on its own axis, and it is the sum of these two movements that constitutes the distance traveled by the cable 24. The amount of travel is determined by the size of the cable drum 20, as well as the entire ratio between drum 6 and cable drum 20. It is the travel of cable 24 that is utilized to unlatch the lock on the door, and the cable is conducted to lock through sheaves mounted on the door closing connecting rods, slides, levers, etc., in such a manner as to maintain the same relative position of the lock bolt to cable drum 20, whether the door is open, closed, or in any intermediate position.

A plate 36 is pivoted at 37 to an anchorage 38 fastened to a main stud 39, and is held against the end wall of a gear housing 14 by tension of the spring 40. When the gear housing 14 rotates in a counter-clockwise direction around the rocker shaft 9 and reaches the limit of its movement, it engages with a notch 41 on a plate 36, which prevents the gear housing 14 from rotating in a clockwise direction under action of the spring 13 which was placed under tensile strain as it wound around the drum 12 during rotation of the rocker shaft 9. The tension of spring 13, which is clockwise in direction, is free to act on rocker shaft 9 as soon as stud on drum 5 has passed dead center by virtue of the pawl 6 overriding the ratchet 4. As gear housing 14 is prevented from turning in a clockwise direction by notch 41, the only possible escape for energy stored up in spring 13 is to drive the spur gear 15 in a clockwise direction, the intermediate gear 22 in a counter-clockwise direction, the cable drum pinion gear 21 in a clockwise direction, and the spur gear 16 in a counter-clockwise direction. As the gear 16 and the cam arm 18 are both keyed to the posterior section of the rocker shaft 9, the outer end of cam arm 18 will move through an arc in the same direction that gear 16 rotates, and as the outer end of this arm is coupled to the movement of the door through a system of slides, arms, toggles, or other means, it can thus be seen that the torque of spring 13 is expended in opening the door. An additional force stored up in the spring or springs of lock and/or lock actuating unit is utilized through tension placed on the cable 24, which produces a torque on the cable drum 20 in the same direction as that of spring 13. The bolt of the latch or lock is adjusted to clear the striking-plate just before the stud on drum 6 reaches dead center, but the torque of spring 13 is not available for opening the door until after this stud has passed dead center. During this interval, which is of short duration, the door could be pushed open by hand, wind or gravity, and should that occur, the gear housing 14 would be rotated a considerable distance beyond the notch 41 on plate 36, but as soon as the stud on drum 5 had passed dead center, the spring 13 would violently snap it back against the notch 41.

To provide for a gradual dissipation of energy in such a case, the damper governor 44, shown in Fig. 15, which is a front view of area 15-15 of Fig. 17, is placed so that the worm shaft 45 is in mesh with the worm gear 11. The governor consists of the worm shaft 45, supporting a collar 46 to which are fastened, one end each, three flat springs 47 having weighted brake shoes 48 attached to the free ends and suspended in position to bear against the internal circumference

of the brake drum 49. If a condition arises where the energy of spring 13 cannot be utilized to open the door, the sudden clockwise rotation of the rocker shaft 9 will develop a very rapid rotation of the governor 44, which by centrifugal force will expand the weighted brake shoes 48 forcibly against the interior surface of brake drum 49, producing a damping action on the expenditure of energy stored in spring 13 and cable 24. The worm gear ratio and weights of brake shoes are so proportioned that normal rotation of the rocker shaft 9 is not retarded. An arm 50 is pivoted to a bracket supported to the framework in such a position that a pin 51 is held in contact with the periphery of the drum 5 by action of the tension spring 52. The drum 5 has a slot in such relationship as to become adjacent to pin 51 a few degrees after the stud on the drum 5 has passed dead center, which allows the pin 51 to drop into this slot. This slot is carried around for a sufficient distance to allow the stud to reach back center, at which point the pin 51 will be adjacent to and will enter a deeper depression at the end of the slot. This constitutes a friction stop to hinder any unwarranted rotation of the drum 5.

A pair of contacts 53 connected in the control circuit of a motor contactor 54 are mounted in relation to an arm 50 so that the circuit is closed when the pin 51 is riding the outer periphery of drum 5, but is open when the pin 51 is riding in the slot, or has entered the deeper depression at the end of the slot in the drum 5. This acts as a limit switch to stop the motor after the opening cycle has been completed. The slot in the upper end of the connecting rod 7 allows the drum 5 to complete its operation, regardless of whether the door immediately opens or not.

When conditions do not permit the cable to be conducted to the lock on the door, such as when a solid metal door is to be handled, in which case it might be difficult to conceal the cable, and where dead bolt locks are used, or where, for any other reason, it is undesirable to bring the cable to the lock on the door, then a device installed in the door jamb is employed to perform the operation of unlocking the door. Details of this device are shown in Figs. 3, 4 and 5 and are essentially a steel wedge 25, running in guides (not shown), having a spring 26 normally holding the wedge 25 against a stop on guides so that the small end of the wedge is between the back rollers 27 and the roller 28 of thrust member 29. When cable 24 is caused to travel, the wedge 25 is moved in such a direction as to exert a force between rollers 27 and roller 28, which causes the thrust member 29 to move out through slots in striking plate 30 to the extent shown by the dotted outline in Fig. 5, which is a sectional view through 5-5 of Fig. 3. The thrust member is shown adapted for automobile usage where the striking plate usually has a second catch 31 and the thrust member has sufficient power to force back the bolt against the tension of the stiff springs encountered in certain types of automobile locks. The thrust member in this case has an additional extension 32 which allows the door bolt to ride over the second catch 31 without engaging with it. For ordinary door latches the thrust member 29 has only one extension.

For latches which have separate sections of the bolt arranged to ride on the face of the striking plate, allowing only the center portion of the bolt to enter the recess in the striking plate for

the purpose of accomplishing a "dead bolt" effect, the shank of the thrust member 29 is provided with cams at the top and bottom and the striking plate has slides at the top and bottom of its recess and are held against the shank of the thrust member by springs, and are capable of being forced upward and downward respectively by the action of the cams on the thrust member. These slides engage with the cams outside of the area of the recess in the striking plate so that there will be no interference with the bolt of the latch. The first movement outward of the thrust member moves the slides upward and downward, thereby enlarging the recess in the striking plate a sufficient amount to let the separate sections of the bolt enter the recess, which action automatically relieves the latch of its "dead bolt" effect and permits the thrust member, which now contacts the bolt of the latch, to force it out of the recess in the striking plate, thus unlocking the door.

For dead bolt locks, the steel wedge 25 is replaced with a rectangular steel member running in guides and provided with a spring 26 that normally holds it against a stop on guides. The face of this steel member is recessed to accommodate the bolt of the lock, and this recess is extended upward an equal distance above the bolt of the lock. The side of this steel member adjacent to the top portion of its recess, is slotted out in the direction that the door is arranged to swing, so that when this steel member has been pulled downward a distance sufficient to align the slot in its side with the bolt of the lock, then the bolt is free to move through this slot as the door swings open. The steel sliding member is arranged to be held in this position by a catch until the bolt of the lock again enters the slot, at which time the catch is released, allowing the spring 24 to return the steel member to its normal position.

Another adaptation combining the principles of the wedge type and those of the dead bolt arrangement is shown in Fig. 8, with Figs. 9 and 10 as sectional views. In this case the steel slide member carries the striking plate 30, which rides in a slot of the mounting plate, so that when the steel member has been pulled downward, as shown by the dotted lines, then the striking plate 30 has been moved downward a sufficient distance to disengage with the bolt of the latch, and the door is free to swing open. The steel sliding member would ordinarily be returned to its normal position by a spring, although the drawings show a cable attached at the top. The purpose of this cable will be described later. Fig. 10 shows the striking plate 30 as of the double catch type, but the arrangement is equally efficient when used with a striking plate recessed and slotted in a similar way to that described for use with dead bolt locks.

Fig. 14 is a view of an ordinary lock used on an automobile door, showing an adaptation for operation by the cable 24. A lever 33 is attached to the lock in such a way as to pivot on the stud 34 and is held in normal position by the spring 35. This lever makes contact with a lug 36 extending from the bolt 37, and when the cable 24 is made to travel, the lever 33 in moving with it, presses against the lug 36, forcing the bolt 37 to move away from the striking plate and allows the door to swing open. The ratio between the movement of the bolt 37 and the cable 24 is determined by the length of the lever 33.

75 The foregoing is mainly a description of the

parts and methods employed to unlock a door, although reference has been made to some parts that function in both the unlocking and locking cycles.

A cam 55, free to rotate on the main shaft 3, has a pawl 56 supported in position to engage with a ratchet 57 which is keyed to the main shaft 3, and able to rotate cam 55 in a clockwise direction, but not in a counter-clockwise direction. This is shown in Figs. 16 and 17. A sectional view of Fig. 17 through line 19-19 is shown by Fig. 19. A roller 58 is mounted on a stud extending from the face of the cam arm 18 in alignment with the cam 55. The outer end of the cam arm 18 has a connection through some system of levers, toggles, cables, or other means, with the door, one adaptation of which is shown in Figs. 12, 13, 16 and 17. This is a development for use with hinged doors, particularly automobile doors. It will be seen that when the cam arm 18 is caused to move in an arc around its axis in a counter-clockwise direction, it will impart a right hand horizontal motion to slide the carriage 59 through a connecting rod 60. Likewise, a left hand motion will be set up in the slide carriage 59 when the cam arm 18 transcribes a clockwise arc. This horizontal movement is transmitted to the door 61 through the connecting rod 62 and door bracket 63. The connecting rod 62 is pivoted at both ends and can thus follow the arc transcribed by the bracket 63 as it swings with the door 61. A trigger 64 pivoted to the cam arm 18 and having a shoulder 65 that acts as a stop to limit the downward movement of a trigger 64 in relation to the cam arm 18, and held in this position by tension spring 66, is so adjusted as to come in contact with the plate 36, but spring 66 allows trigger 64 to override the plate 36, while cam arm 18 is moving in a direction that will cause the door to open, or with the door as it opens, but any movement of the cam arm 18 in an opposite direction would create a toggle action through the trigger 64 against plate 36a, forcing the notch 41 to disengage with the gear housing 14, allowing the gear housing assembly to move with the rocker shaft 9 as it returns to its normal position when the door is being closed.

If the door is in an open position, the roller 58 has landed against the cam 55 at its smallest radius 67. Thus, when the motor 1 is caused to operate in a direction that will rotate the main shaft 3 in a clockwise direction, the ratchet 57 will engage with pawl 56, forcing cam 55 to interpose its body continuously increasing radii between its axis and roller 58, compelling cam arm 18 to swing in a clockwise arc, imparting a movement to the system of coupling to the door of such direction and magnitude as to drive the door shut.

A pin 68 free to slide longitudinally in a hole bored through the bed plate 69, has the nose rounded and is capable of entering a depression 70 in the hub of the cam 55 when such depression is adjacent to pin 68. The depression 70 is shaped with a straight side parallel to the axis of the pin 68, and having the other side sloped so that after the pin 68 has entered the depression 70, then the cam 55 would be prevented from rotating in a counter-clockwise direction, due to the fact that the straight side of the depression 70 bears against the side of the pin 68, but a clockwise rotation of cam 55 is possible, as the sloping side of the depression 70 will cause the rounded nose of pin 68 to ride

out of the depression by forcing the pin 68 to move in opposition to the spring 71.

A pair of contacts 72 connected in the control circuit of the motor contactor 54 are mounted in such relation to the pin 68 that the circuit is closed when the pin 68 is riding on the straight part of the end of the hub of cam 55, but is open when pin 68 has entered the depression 70. This acts as a limit switch to stop the motor 1 after that part of the cam 55 having the greatest radius has cleared the roller 58. This clearance is sufficient to allow free movement of the cam arm 18 without interference from cam 55. Where desirable, the mechanism can be arranged to unlock the door and then drive the door open, as well as being capable of driving the door closed. This is accomplished by the addition of a second cam having only a portion of its body constructed with increasing radii so as to allow the unlocking cycle to function before this second cam engages with roller 58, which would be wide enough to accommodate both the opening and closing cams. Also where desirable, the mechanism can be arranged to unlock the door and then drive the door open and to hold the door open until the control circuit is made to trip a catch, which allows the door to close by spring action. This catch may be a separate unit, or the cam 55 may be provided with a second set of contacts that would stop the motor 1 before the cam 55 clears roller 58, thus holding the door open. The door would be released by causing the cam 55 to rotate a sufficient distance to clear roller 58, at which point the control circuit would be opened by the contacts 72. In this case, the device is not fully selective as the door cannot be closed manually, but it is selective in that it can be opened and closed either manually or mechanically.

A suitable cushion is provided to absorb the inertia of the door as it nears the end of travel, especially where actuated by springs, but in any case where conditions warrant. These cushions may be of rubber, or where necessary, an air or oil door check may be used. Such a check may be built into the mechanism as an integral part, or may be attached to the door as a separate unit. Where one movement of the door is actuated by springs, the speed of this movement can be controlled by the use of a damper governor similar to that shown in Fig. 15.

A fundamental circuit is shown in Fig. 20. A special reversing contactor, consisting of coils 73 and 74, each provided with single pole, double throw contacts 75 and 76 respectively, is shown connected in such a way as to be capable of operating a series motor in either direction. Split phase, single phase, and two or three phase motors can be controlled by providing double pole, double throw contacts at 75 and 76. The control circuit consists of the coils 73 and 74, the open and close buttons 77 and 78, the limit switch contacts 53 and 72, and the key switch 79.

For use on an automobile, one end of the circuit is shown grounded to the chassis at 80, and the other end of the circuit 81 is connected to the car battery. In this case, a link 82 bridges two terminals 83 and 84 located in an accessible place, which provides a means of isolating the circuit by removing the link 82, but of more importance, it provides a place for connecting an outside battery in case the car battery has become discharged while standing with the door locked, in which case it would not be possible to unlock the door by use of the key switch 79, and for this reason, it has been made possible to connect an

outside source of electrical energy between the terminal 83 and some grounded part of the automobile. The possibility of requiring such aid, however, is very remote. When the button 77 is closed, or when the key switch has been turned so that its left hand contacts are closed, a circuit has been completed from one side of the line, or of the battery through lead 81, button 77 or contacts of key switch 79, coil 73 to the other side of line 80, or to the battery through ground on the chassis, as the case may be. The coil 73 on being energized will attract its armature which moves the contacts 75 so as to open the normally closed and close the normally open contacts, thus completing a circuit of such relative direction through its field and armature in the case of a series motor, or of such relative instantaneous direction through two of its windings in the case of split, two or three phase motors, as to cause the motor to operate the mechanism in a direction suitable for opening a door.

The button 77 or key switch 79 may be returned to normal as soon as the drum 6 has rotated a distance sufficient to have closed the contacts 53, which maintain the circuit through coil 73 until the drum 5 has rotated a distance sufficient to have opened the contacts 53, at which time the motor will stop. A similar procedure with button 78 or the right hand contacts of key switch 79 will energize coil 74 which will move contacts 76 so as to operate the motor in a direction suitable for the mechanism to close a door. The limit switch 72 is used in this case.

The control circuit shown as part of the circuit of Fig. 20 is very simple and requires the buttons 77 or 78 or the contacts of key switch 79 to be held closed until the limit switches 53 or 72 have been closed, and it further requires these contacts to be opened before the completion of the cycle of operation the mechanism is engaged with. If these starting contacts are not opened, the mechanism will continue to operate repeatedly, which of course will do no harm, other than to use electricity and allow a certain amount of wear to the mechanism. While these faults are not intolerable, nevertheless a more elaborate system is applicable when desired.

To provide means of unlocking and opening, or partly opening, a door, particularly a hinged door and especially a door of an automobile, a device and circuit shown schematically in Fig. 6 is used. This is intended to operate any of the "door jamb" units shown in Figs. 3, 4, 5, 8 and 10 and described in preceding paragraphs. The drive consists of a series motor 1 having a field 85 and an armature, a train of gears 87 and a cable drum 88. A cable 89 is conducted around one or more sheaves, one being shown at 90, to a sliding member or wedge 25, and in the case of an automobile, both the drive mechanism and cable are installed so as to be accessible only from the interior of the car. In some instances, as with certain types of automobile sedan bodies, the door jamb between the front and rear door is not deep enough to accommodate a unit like that shown in Fig. 3, and in such case a unit like that shown in Fig. 3 would be used. The spring 26 would be replaced by the cable 91 shown attached to the top of the slide member in Fig. 9, which would be conducted around sheaves to a second cable drum 92. The cable drum 88 would wind up cable 89, while cable drum 92 would pay out cable 91, and vice versa. If desired, the double cable system may be used with any of the

door jamb units when coupled to the device shown in Fig. 6. The dead bolt type would in this case have a contact in the unit in place of the catch, and this contact would energize the motor for returning the slide member to its locked position after the bolt of the lock had entered the slot and closed the contact.

The circuit, Fig. 6, employs a button operated switch 93 and a key operated switch 94. These switches are essentially double pole, double throw switches, made up of flat springs similar to telephone construction. The movable springs normally make contact with two of the stationary contacts, but are capable of being moved away from these and against the other two stationary contacts. To follow telephone practice, these switches could be described as having two break and two make contacts. The switch 94 is operated through the medium of a cylinder lock which may be installed, conveniently for use, outside the enclosure to which the door gives access. There is a key for this lock and an electric circuit connected with the lock so that the circuit is completed by placing a key in the lock. Two cams are mounted on the shaft that carries the cable drum 88 or the cable drums 88 and 92. These cams operate limit switches 95 and 96 and are adjustable and can be set for proper cable travel. When either of the switches 93 or 94 are operated, a circuit is completed from one side of line or battery 97 through the contacts of switch 93 or the contacts of switches 94 and 93, armature of motor 85, limit switch 95, and field of motor 85, to other side of line 98, or battery via ground on the chassis, in the case of an automobile. The current that flows through the motor will be of such relative direction through its armature and field as to cause it to drive the mechanism in a direction that will unlock the door. The switch 93 or 94, as the case may be, must be held until the cams have rotated a distance sufficient to have opened the limit switch 95 and closed the limit switch 96, at which time the motor will stop and the door will open or partly open. When the switch that had been used to unlock the door is released, a circuit is completed in a similar way as before, but through the armature 86 in an opposite direction, and through limit switch 96 instead of through limit switch 95. The motor will stop automatically when the cams have rotated a distance sufficient to have opened the limit switch 96 and closed the limit switch 95, at which time the slide member or wedge 25 has returned to normal. It will be noted that while the motor is operating in one direction through one of the limit switches, the other limit switch is preparing a circuit for operating the motor in the opposite direction.

Where it is only desired to have the door open partly so as to clear the lock to prevent the door from being locked again when the switch 93 or 94 is released, then a spring 99 set in the back of the door, as shown in Figs. 7 and 11, is used to open the door part way as soon as it is unlocked. Where it is desired to completely open the door, then a spring door check is coupled to the door by some system of toggles, or by other means, so that the spring of the door check will open the door and the end of travel will be cushioned by the air or oil escapement of the door check.

The unlocking, opening and closing operations may be described as follows. Referring to Figs. 18 and 19, shaft 3 can be caused to rotate in either direction by means of the control circuit, motor, drive gears and gears 2. The drum 6

bored to a free fit, is mounted at one end of shaft 3, and the cam 55 bored out to a free fit, is mounted near the other end of shaft 3. From this it will be understood that if we disregard the pawls 5 and 56, the shaft 3 is free to turn within the drum 6 and the cam 55. The ratchets 4 and 57 are keyed to the shaft 3 with the teeth of each set in opposite directions, so that when the shaft 3 rotates in one direction, the pawl 5 will cause the drum 6 to rotate, but when the shaft 3 rotates in the other direction, the pawl 56 will cause the cam 55 to rotate. The cam 55 is prevented from turning in the wrong direction by the pin 68. The drum 6 is hindered from rotating by the action of the spring 13, which through the bell crank 8 and connecting rod 7, will tend to hold the stud on the drum 6 in its back center position and the action of the pin 51 which enters a depression in the drum 6.

Figs. 18 and 19 show the normal position of the drum 6, the connecting rod 7 and the entire rocker shaft assembly. When the mechanism for unlocking and opening the door is set in operation, the following action takes place. The main shaft 3 rotates in such a direction that the ratchet 4 will engage the pawl 5 and turn the drum 6, but the cam 55 remains stationary. It will be seen that one-half of a revolution of drum 6 will, through the connecting rod 7, impart a rotary motion to the bell crank 8 and the anterior section or rocker shaft 9. This is the section having the following members keyed to it, the damper governor gear 11, the spring drum 12, the bell crank 8 and the gear 15. During this rotary motion of the anterior section of the rocker shaft 9, the spring 13 would wind up on drum 12. Fig. 13 shows the position of the gear housing 14 after about one-fourth of a revolution of drum 6.

Considering Fig. 18 from a front view of the mechanism, it will be seen that when the gear 15 turns in a counterclockwise direction, it will drive the intermediate gear 22 clockwise, the pinion 21 counter-clockwise, and would try to rotate the gear 16 in a clockwise direction, but the gear 16 cannot rotate any further in this direction as the door is closed and the cam arm 18 is in the position shown in Fig. 16. As the gear 16 cannot turn, but only tends to close the door tighter, the only alternative is for the pinion 21 to rack itself around the gear 16 in a direction opposite to that in which it tried to rotate gear 16; in other words, it would cause the gear housing 14 to rotate on its axis (shaft 9) in a counter-clockwise direction. By the time the stud on the drum 6 had reached the opposite side of its travel around the center of the shaft 3, the gear housing 14 would have reached the position shown in Fig. 16. During this motion the cable 24 had been winding up on drum 20 as well as being drawn further around sheave 17, see Fig. 16, and the ratio of the several parts involved has been so calculated as to provide the proper amount of travel in cable 24 to unlock the lock. This completes the unlocking cycle.

Up to the time that the stud on the drum 6 had reached, but not passed, dead center, the torque on gear 16 had been clockwise, but the moment that the stud on drum 6 passes dead center, the spring 13 and the strain on cable 24 will be freed of the power applied to them through the connecting rod 7, and this power stored in the spring 13 and the cable 24, is immediately available, without retardation from drum 6, for driving the gear 15 in an opposite direction. The drum 6 offers no opposition other than friction,

for the pawl 5 can override ratchet 4 as the drum 6 follows the connecting rod 7 and the bell crank 8 back to normal. As the torque on the gear 15 is now of opposite value, then it must follow that the entire action of the gear housing assembly will be opposite. But the notch 41 on the plate 36 has blocked the gear housing 14 from returning to normal and so, by "differential" action, the only alternative is to drive the gear 16 in an opposite direction to that of the torque placed on it before. This being counter-clockwise direction, it will be seen by referring to Figs. 18 and 16, that the cam arm 18 will be urged to swing its lower end to the right, opening the door. The motor is stopped at the proper time by the limit switch. During the outward swing of the door, the drum 20 had been paying out cable and the bell crank 8 had been returning to normal, and by the time that the door had completed its opening movement, the lock bolt, or the lock actuating device, was back to its normal position and the bell crank 8 had reached the position shown in Fig. 18, which is as far as the connecting rod 7 and the drum 6 will allow it to turn, thus removing the remaining energy of the spring 13 from the gear 15, and transferring this energy to the connecting rod 7, and serving to hold the drum 6 and the bell crank 8 in the position shown in Figs. 18 and 19, during the other movements of the mechanism. This completes the door opening cycle.

The door may now be pushed shut manually, or it may be closed mechanically. When we cause the shaft 3 to rotate in an opposite direction from that of the unlocking cycle, the ratchet 57 will engage the pawl 56 and turn cam 55 in a clockwise direction. The roller 58 had landed against the cam at 67 when the door opened. Referring to Fig. 16 it will be seen that a clockwise rotation of the cam 55 will through the roller 58, swing the cam arm 18 which begins to move to the left, the trigger 64 will by toggle action against the plate 36, release the gear housing 14 so that it may move back with the cam arm 18. This movement of the gear housing 14 is not of course directly proportional to the movement of the cam arm 18, but is as the ratio of the gears 15 and 16. By the time that the cam arm 18 reaches the position shown in Figs. 13 and 16, which means that the door is completely closed, the gear housing 14 will have moved to its normal position in which it was before the unlocking cycle, and would be at a point somewhat higher than that shown by the dotted outline in Fig. 13, for as explained before, the position in Fig. 13 is after about a quarter of a turn of the drum 6. The ratio of the gears 15 and 16, the size of the drum 20, the size of the sheave 17 and the size and disposition of the several sheaves mounted on the coupling to the door, have also been so calculated and designed that where the movement of one part will slack off the cable 24, compensation is provided by a proportional movement of another part, so as to maintain the cable 24 taut in all positions of the door. The motor is stopped at the proper time by the limit switch. This completes the closing cycle.

We claim:

1. A door operating apparatus comprising a movable bolt mounted upon the door, a part adjacent to the door with which said bolt interlocks, a bolt moving mechanism for moving said bolt, a door moving mechanism for moving the door, a power device for actuating said bolt moving mechanism and door moving mechanism, means forming a part of the connection between the

power device and said connections, for first actuating the bolt moving mechanism before the pressure of the door moving mechanism has been applied to said bolt and after the bolt has been moved to unlocking position for then actuating the door moving mechanism to open the door, means brought into action for said power device for storing up energy during the unlocking movement of the bolt, an apparatus for transferring said stored up energy to the door to apply opening pressure on it and means for delaying the transfer of said stored up energy to said door until the bolt has been moved to its unlocking position.

2. A door operating apparatus comprising a movable bolt, a part connected with the door with which said bolt interlocks, a bolt moving mechanism for moving said bolt, a power device for actuating said bolt moving mechanism, means brought into action by said power device for 20 storing up energy during the unlocking move-

ment of the bolt and apparatus for transferring said stored up energy to the door to apply an opening pressure on it, and positively acting means for delaying the transfer of said stored up energy to said door until the bolt has been moved to its unlocking position.

3. A device of the kind described, comprising a door, a lock having a movable bolt, mounted on said door, a part with which said bolt interlocks, 10 a bolt moving mechanism for moving said bolt, a door moving mechanism for moving said door, two separate means for starting said bolt moving mechanism and door moving mechanism, one on the interior of the device with which the door is used, and the other accessible from the exterior of said device with which the door is used, and means for applying a closing pressure to the door during the unlocking cycle, to relieve the bolt of friction due to pressure on the door.
